UNITED STATES PATENT OFFICE.

EDWIN C. JACOBS, OF NORWALK, OHIO.

DEVICE FOR THE STUDY OF COMMON FRACTIONS.

1,224,748.

Specification of Letters Patent.

Patented May 1, 1917.

Application filed December 12, 1913, Serial No. 806,209. Renewed November 22, 1916. Serial No. 132,913.

To all whom it may concern:

Be it known that I, EDWIN C. JACOBS, a citizen of the United States, and resident of Norwalk, in the county of Huron and State of Ohio, have invented certain new and useful Improvements in Devices for the Study of Common Fractions, of which I hereby declare the following to be a full, clear, and exact description, such as will 10 enable others skilled in the art to which it appertains to make and use the same.

The objects of the invention are to provide a disk or disks graduated to fractional parts of a circle and having fractional 15 quantities displayed thereon in a graphic manner, so as to illustrate at a glance a series of fractional parts of a circle, and the relations of the fractional parts to each other, and also includes a base provided with 20 a center pin upon which the disks are revolute.

A ruler is also preferably employed having radial edges extending from the center of the disk beyond the circumference by 25 means of which radial lines can be drawn and the corresponding degrees upon the margin can be read.

The invention is designed to assist in the drawing of fractional parts of a circle, and 30 in drawing geometric figures such as stars, the points of which are spaced equally apart, and inclose equal angles.

The disks may be two or more in number 35 and there may be displayed upon one disk the single or unitary fractions only with arcs of circles, and showing their relative values, and upon the other disk all the fractions comprising each unit can be displayed, up to the limit of needed use in ordinary 40 school work, or only one disk may be used if desired, illustrating either method of grouping fractions, or additional disks can be added to increase the number of fractions, since arcs illustrating all fractions can 45 not be drawn upon a single disk.

The invention is illustrated in the accompanying drawings, hereinafter further described with the method of its use, and is 50 specifically pointed out in the claims.

In the accompanying drawings Figure 1 55 is a plan view of the device showing one method of its use; Fig. 2 is a plan view of a modified form of disk. Fig. 3 is a side elevation of the disk and a base plate upon which the disk is mounted.

In Fig. 1 a disk A is shown having the

degrees of a circle marked upon a graduated edge D, and containing arcs of definite portions of the circle separated by radial lines, and having plainly marked thereon the divisional part they represent, as, 8, indicating that the arc upon which 8 is marked represents $1/8$ of a circle, and the radiating lines A⁸, B⁸, C⁸, from its ends extend to the graduated margin, expressing thereon the 60 number of degrees contained in such fractional part of a circle, at 45° . A ruler R pivoted at the center of the disk at C has a radial edge R' by means of which any radial line can be followed to its corresponding 70 degree.

The same is true of all the fractional parts, such as the fraction $1/18$ designated by the numeral 18, and indicated on the graduated margin by 20° , and as the fraction $1/20$ indicated upon the margin by 18° or the fraction $1/7$ indicated by the numeral 7 and upon the margin by $51-3/7^\circ$.

In every case the fraction is more simply indicated if it is a single or unitary fraction, 80 by marking only the denominator in the corresponding arc which may be long or short provided its marginal radial lines run to the graduated margin.

For instance, the arc 8 has a radial line at 85 each end and 45° are included between them. Also the arc 10 has radial lines at each end including 36° between them. It is therefore easy for the student to see at a glance that the difference between $1/8$, and $1/10$ is 9° 90 or $1/40$ and 40 can be marked directly upon this smaller arc as shown in Fig. 1.

Also it is evident the sum of fractions included between two radii equals the arc included between the same radii since as 95 shown in Fig. 1,

$$1/36 + 1/45 = 1/20$$

or 18° ; also two arcs of $1/8$ each equal 90° or $1/4$.

100

In fact fundamental operations in simple fractions can readily be understood at a glance. This same principle can include operations in more complicated fractions, having their numerators either single or plural. 105

As shown in Fig. 2 the segments upon the disks represent fractional arcs or circles and the numerals the denominators of the common fractions represented by said arcs.

The difference between the fractional 110 values of fractions not having unitary numerators can be read on a graduated margin

D in degrees and reduced to common fractions, or read on the dial of Fig. 1.

For instance employing the ruler R first on radial lines L and then on radial line M, 5 a difference of 42° is read between the arcs representing $3/10$ and $5/12$ and equals $7/60$. The horizontal line H it is understood is used as a common starting point or base line. The ruler R pivoted upon the center C 10 can revolve so that its radial edges register with any of the radial lines and it should extend beyond the graduated margin.

The disk or dial shown in Fig. 2 can be used in connection with a radial ruler R to 15 measure differences between fractions having a unit for a numerator and also to indicate differences between fractions having plural numbers for numerators.

In the arrangement shown in Fig. 1 a 20 great number of arcs of different lengths can be drawn when the numerators are units, and in the arrangement shown in Fig. 2 both units and plural numbers can be used 25 for numerators. For convenience in use the disk A is mounted upon a base A' which is provided with a needle A² that projects through the center C of the disk. The ruler R is also pivoted in this disk and preferably extends beyond the disk A so that the graduations or any of them can be marked upon 30 a piece of paper E, inserted between the disk and its base and from the points thus indicated the various angles of geometric figures can be drawn to produce stars or 35 other effects.

The radial ruler is provided with regularly spaced openings o, o, by means of which arcs of circles of specified diameter can be drawn by a pupil by inserting the 40 point of a pencil therein. One or more small holes P, P at the left of the center and on the base line are shown in Fig. 1, which pass through the disk A, and are used as centers to enable the pupil to draw a larger circle without the pivoted ruler.

Openings Q, Q are also made at spaced intervals in the disk through which arcs and circles can be drawn if desired.

When, however, the radial ruler is used 50 circles and arcs can be drawn through spaced openings o, o therein.

Having described the invention what I claim as new and desire to secure by Letters Patent is:

55 1. In a device to assist in the study of fractions, a foundation disk having a central upwardly extending point, a disk centrally mounted and rotatable upon said point, said disk graduated in degrees of a 60 great circle upon its edge, said disk having represented thereon radial lines, including fractional parts of the circle between them

and arcs included between said radial lines, the fractional amount being represented upon each arc in common fractions, and a 65 ruler revolvable upon said center pin and having a radial side extending beyond the graduated edge, whereby the sum of any plural number of the fractions represented by said arcs and differences between them 70 can be read in degrees of the great circle, and also in divisions of said arcs.

2. In a device to assist in the study of fractions, in combination, a disk having its outer edge graduated in degrees of a great 75 circle, and provided with a series of arcs, representing divisional parts of the circle, and with a representation of a common fraction upon each arc, the limits of each arc being designated by radial lines, and a 80 ruler rotatable upon the center of said disk, and having a radial edge, whereby the number of degrees subtended by each arc or portions of an arc can be read upon said 85 graduated margin of said disk.

3. In a device for the graphical representation of operations in fractions, a disk having a radial base line extending thereacross, and provided with a graduated margin, arcs 90 of circles originating in said base line and radial lines defining said arcs, said arcs designating fractional parts of the circle, additional radial lines, further subdividing some of these arcs, the fractional values of said arcs being represented thereon in common 95 fractions, and a pivoted ruler having a radially extended edge, adapted to correspond in turn with said radial lines, and serving to register with the graduations on said graduated edge.

4. In a device for the graphical representation of operations in common fractions, and also adapted for the construction of angles in geometric forms, a centrally pivoted disk, provided with a graduated edge, 105 and a radial base line, a series of arcs, of different lengths, and limiting radial lines therefor represented upon said disk, said arcs designated by the denominators of the common fractional parts they represent, and a centrally pivoted ruler having a radial edge adapted to register with said radial lines in turn and with the graduations on said edge, and extending beyond said edge, whereby the fractional amount included between any two of said arcs or the amount of difference between them can be read upon said graduated edge.

In testimony whereof, I hereunto set my hand this 4th day of September, 1913.

EDWIN C. JACOBS.
